UNITED STATES PATENT OFFICE

149,372

DESIGN FOR A COOKING STOVE

Daniel P. O'Keefe, Los Angeles, Calif.

Application April 19, 1946, Serial No. 128,769

Term of patent 14 years

(Cl. D81—25)

To all whom it may concern:

Be it known that I, Daniel P. O'Keefe, a citizen of the United States, residing in the city of Los Angeles, county of Los Angeles, State of California, have invented a new, original, and ornamental Design for a Cooking Stove, of which the following is a specification, reference being had to the accompanying drawing, forming a part thereof.

Fig. 1 is a perspective view of a cooking stove showing my new design; and

Fig. 2 is a fragmentary view showing the end of the front control panel. The dominant features of my design reside in the portions shown in full lines.

I claim:

The ornamental design for a cooking stove, as shown and described.

DANIEL P. O'KEEFE.
